UNITED STATES PATENT OFFICE

ROBERT HOE, OF HYDE PARK, NEW YORK

WASHING MACHINE

Application filed September 29, 1926. Serial No. 138,356.

My present invention relates to improvements in washing machines, and particularly of the type in which the washing is done by the dashing of the water and clothes by means of reciprocating bells, and more particularly one in which washing apparatus can be brought into operative relation with any of the usual household stationary wash tubs.

My invention will be best understood from the following description and the annexed drawings of an illustrative embodiment in which Fig. 1 is a side elevation showing my washing apparatus connected to a stationary tub, the tub being shown in section; Fig. 2 is a front view of the arrangement of Fig. 1, the tub being shown in section; Fig. 3 is a plan view of the arrangement shown in Figs. 1 and 2; Fig. 4 is another plan view of the arrangement shown in Figs. 1 and 2 but in which the washing devices have been disconnected and swung out of the way while the wringer is in operative position; Fig. 5 is an enlarged view, partly broken away, of a part of the apparatus looking from the left in Fig. 1; Fig. 6 is a section on the line 6—6 of Fig. 5; Fig. 7 is an enlarged view of a portion of the devices shown in Fig. 5, but with some of the parts in slightly different positions and with the cover of the gear box removed for a better disclosure; Fig. 8 is a detailed view showing some of the parts of Fig. 2 in a different position, and Fig. 9 is an enlarged section of a part of Fig. 8, showing a detail.

Like reference characters indicate like parts in the several views.

In the arrangement shown in the drawings which I have selected for purposes of illustration, the washing apparatus is supported on a base 10 provided with castors or the like by which it may be readily moved over the floor on which it rests, this base having a column 11 on which is supported a gear box sleeve 12, the latter being rotatable on the column 11 and also vertically adjustable thereon, as well be described hereinafter.

On the sleeve 12 is a casing 13 which, for brevity, I will call a gear box, on which is mounted a motor 14 connected by a belt 15 through suitable pulleys to a shaft 16 connected to the gears in the gear box 13.

Extending from the gear box 13 and connected to shaft 16 through connections to be described hereinafter, is an oscillatory driven shaft made up of two parts 17 and 18 and connected, when the parts are in operative position, with their axes in alignment, by a tongue and groove clutch, the tongue 19 being formed on the end of the part 18 and the groove 20 being formed in the end of the part 17. This tongue and groove clutch connection provides a means by which power is transmitted from one shaft to the other. The shaft 17 extends through the gear box 13 and the clutch connection is, therefore, just outside of the surface of this gear box.

The outer end of the shaft 18 is carried in a bearing 19' supported by a bracket 21 hingedly connected to the gear box 13 by the hinge pins 22 extending through openings in the lugs 23 formed on the inner end of the bracket 21. By this arrangement, it will be seen that the bracket 21, its bearing 19' and the shaft 18, supported in this bearing and in an inner bearing on the bracket 21, can be turned to the positions shown in Figs. 4 and 7 and such turning will disconnect the two shafts. In addition, it will also be noted that the bracket and its shaft 18 can be entirely removed from the gear box 13 by lifting it upward to remove the lugs 23 from the hinge pins 22.

On the outer end of the shaft 18 is formed, in the illustrative embodiment, a pair of flats 18', as best shown in Fig. 4, and supported on the shaft 18 is an arm 24 having a relatively narrow slot 25 extending from the bottom of its central hub with the sides of this slot engaging the flats on the end of the shaft 18. Preferably these flats are formed back from the end of the shaft so as to leave a projection 26 which serves to keep the arm 24 from longitudinal movement on the shaft.

At each end of the arm 24 is pivotally connected a downwardly extending rod 27, to the lower end of which is fastened a bell 28 by means of the pivot connection 29. The two rods 27 are pivotally connected midway of their ends to a bar 30. This bar 30 has a pin 31 extending into a fixed loop 32 having its ends engaging the bracket 21.

In practice, the rods 27 are each made up of two parts, one on either side of the arm 24 and with the bar 30 extending between these rods. This arrangement, however, is provided merely for purpose of convenience in manufacture and they are, in effect, the same as a single rod and will so be described hereinafter.

Each bell 28 has an upwardly projecting portion 33 with a pair of ears spaced apart at its top, a stop pin 34 connected to the rods 27 extending into the space between these ears to limit the amount of motion which can be given to the bell 28 around its pivot 29. Similarly the loop 32 limits the amount of longitudinal motion which the bar 30 may have.

Preferably, the rods 27 are provided with means by which their effective length may be changed and for this purpose, in the illustrative embodiment, I make the connecting pins 24' removable and provide a plurality of holes 25' in the upper ends of these rods 27 so that the pins may be inserted in any desired set of holes. As illustrated, each pin 24' is provided with a handle at one end and a recess at the other end, this recess being engaged by a locking member 26' mounted to slide on the rod 27. When the locking member 26' is moved upwards, it is disengaged from the recess in pin 24' which can then be removed. The end of arm 24 is then brought opposite another set of holes 25', the pin 24' inserted and the member 26' moved down to lock the pin in its new position.

When the shaft 18 is oscillated, the bars 27 are reciprocated and the bells 28 are moved up and down in the water in the tub T to wash the clothes therein. I have found that it is desirable that the bells should have motion other than a direct up and down motion, and in the arrangement described, the bells may swing to the extreme positions shown in Fig. 8, the pin 31 limiting the sideways motion of the bells and the pins 34 limiting the amount of pivotal motion which the bells may have. As a result, the bells are free to follow any path which the particular quantity and position of clothes in the tub may determine and the water and clothes will be given a motion which I have found to be particularly advantageous in the washing operation.

Each of the bells is preferably a hollow casting made of a generally rectangular form in plan with the length of the bell shorter in the direction of the arm 24 than in the direction of the axis of the shaft 18. This enables the bells to cover a larger area than would otherwise be possible and, at the same time, enables them to freely operate in the tub without being too close together. Moreover, since the pivotal motion is around an axis parallel to the long axis of the bell, this mo-

tion is transmitted to a larger area than would otherwise be possible.

The arm 24 and all the parts connected thereto may be readily removed from the shaft 18 by means of the handle 35. It will be obvious that the arm 24 can be lifted directly upward and then moved laterally to disengage the pin 31 from the loop 32. I have found that it is not necessary to provide any locking connection between the arm 24 and the shaft 18 when the driving arrangement of the flats on the shaft and the slot in the arm 24 is used. When the machine is in operation, the angular pressure developed by the bells 28 moving through the water is sufficient to press the faces of the slot in contact with the flats on the shaft to prevent the lifting of the arm. My discovery that this is sufficient is, of course, of very great advantage, because it does away entirely with any disconnecting device which the user would have to manipulate to release the parts from the machine.

It will be understood that the entire washing apparatus and motor, by reason of being mounting on the movable base 10, may be moved away from the tub, if desired, and it is necessary, therefore, to provide means by which the apparatus can be brought readily into operative position relative to the tub and locked there while the apparatus is working.

The operating parts are adjusted vertically to suit the height of any particular tub by means of the adjustable sleeve 36 on the column 11, this sleeve being moved vertically to the desired position and held there, as by a pin passing through a selected pair of holes 37 in sleeve 36 and a pair of holes in the column.

On the sleeve 12 is a latch arranged to drop into notches formed in the periphery of the extension 39 on sleeve 36. By lifting the handle 40 of this latch, the sleeve 12 and the apparatus it carries may be turned to any desired position and re-locked by dropping the latch into another notch.

On the sleeve 12 are exterior stops 41 held in lugs 42 on the sleeve by a screw or the like, so that the stops may be adjusted lengthwise to limit the approach of the apparatus to the tub. Preferably I provide a stop 41 on each side of sleeve 12. Preferably the stops are made of wood so that the tub is not marred by the stops.

To lock the washing apparatus, by which I mean all parts, except the motor, which are carried on the support, in operative relation to the tub, I provide a pair of interior stops 43, preferably of wood so as not to mar the tub, these stops being attached to stop arms formed of the two pieces 44, 45, having their ends overlapping and with slots in these overlapping portions through which extend bolts so that the length of the arms may be adjusted and locked in adjusted position.

One end of each part 45 is pivotally connected to a hook 46 attached to bracket 21 at its outer end, these hooks being arranged so that the stop arm may be disconnected from the hook, 5 if desired. The end of the part 44 is extended so that it rests on the top of the tub. Preferably the parts 44, 45 are also made of wood.

As will be best seen in Fig. 3, a stop 43 engages two opposite corners of the tub and, 10 by reason of the angular relation of the stop arms and their connection to the outer end of bracket 21, the apparatus is held against motion away from the tub and also crosswise thereof. By lifting the stop arms, the stops 15 are disengaged from the tub and the apparatus can then be moved away.

In practice I find that the interior stops 43 are usually enough to hold the apparatus in proper relation to the tub because the reaction of the bells against the water tends to slightly tilt the base 10 away from the tub, which tilting is resisted by the stops 43 and there is seldom any tendency to move the apparatus closer to the tub. Hence in practice, 20 the exterior stops 41 are preferably fixed so that they are not actually in contact with the exterior of the tub, and this is advantageous because it avoids any possible rubbing of such exterior. On the other hand, the presence of 25 the stops 41 prevents any possible movement of the apparatus toward the tub in case the clothes or the like in the water become positioned so as to produce a motion in that direction.

35 Bracket 21 is held in operative position with its end against the gear box by a latch 47 pivoted at 48 on the gear box 13 and turned clockwise in Fig. 5 by a light spring 49 which presses a pin 50 against a side of the latch. A 40 latch toe 51 drops between a pair of stops 52 on bracket 21 when the bracket is turned into operative position, a cam piece 53 on the bracket cooperating with a cam piece on the latch to turn the latch counterclockwise as 45 the bracket is moved into operative position.

In order to prevent undue strain on the hinge pins 22 arising from any twisting movement which the bells 28 might give to it as they move in the water of the tub, I provide a pair of spaced lugs 21' on bracket 21 on the side opposite the hinge and a fixed lug 22' on the gear box 13, the faces of the lug 22' fitting snugly against the faces of the lugs 21' when bracket 21 is in operative 50 position. This arrangement will resist any tendency of bracket 21 to rotate on the axis of shaft 18.

In the illustrative embodiment, the shaft 55 60 17 is oscillated by the following mechanism: The shaft 16, driven by the belt 15, extends into the gear box 13 and has a bearing at its inner end. On the shaft is a worm 54 meshing with a worm wheel 55 on a crank shaft 56 supported in bearings in a frame 57 in the 65 gear box. This frame 57 is provided with

ears 58 which rest on lugs 59 at opposite sides of the gear box, being held thereto by suitable screws, the frame 57 being independent of the walls of the gear box and its cover plate 60.

On the outer end of shaft 56 is a wheel 61, this wheel being a gear wheel for a purpose to be described hereinafter. The wheel 61 carries a crank pin 62 on which is a pitman 63 connected to a crank 64 fastened to the shaft 17. It will be obvious from this that the rotation of the driving shaft 16 will cause the shaft 17 to oscillate and with it the shaft 18, thus reciprocating the washing bells.

In conjunction with the washing devices proper, it is desirable to have a wringer and a wringer operating device, and to this end, I have provided a driving shaft 65 extending through the wall of the gear box 13 and parallel to the shaft 17. A bracket 66 is hinged to the gear box by hinge pins 67 projecting through lugs on bracket 66. A wringer frame 68 has its rollers driven by a wringer shaft 69 through the usual gearing, this shaft 69 being in axial alignment with shaft 65 when the parts are in operative position. A clutching connection between shafts 65 and 69 is provided by the clutch members 70, 71 of a common type, this clutch connection being arranged so that when the bracket 68 is swung on its hinge, the shafts 65 and 69 will be unclutched.

It is desirable that the wringer shaft 69 be capable of rotation in either direction and I provide the driving mechanism with arrangements so that this can be accomplished.

In the illustrative embodiment, shaft 65 has loosely mounted thereon a gear 72 meshing with the gear teeth on wheel 61 and also loosely mounted on shaft 65 is another gear 73 driven through an intermediate gear 74 by a gear 75 fastened to the shaft 56. Each of the gears 72 and 73 has clutch teeth formed in its adjacent faces and between such adjacent faces is a clutch collar 76 connected to the shaft 65 but free to move longitudinally thereon. The collar 76 has a groove 77 in which is an operating pin 78 on the end of a lever 79 fastened to a vertical shaft 80 extending through a bearing in the frame 57 in which bearing it is rotatable and slidably mounted, being held downward by a spring 81. The shaft 80 extends through the cover 60 and is provided with an operating handle 82. In the top of the bearing for shaft 80 is formed a number of detent recesses which can be engaged by a pin 83 on shaft 80.

With the parts in the position shown in Figs. 5 and 6, the gears 72, 73 freely rotate on shaft 65 and the latter remains stationary. When it is desired to drive such shaft, the handle 82 is turned to move the clutch collar 76 into engagement with the desired gear,

and this will start the shaft 65 in motion. It will be obvious that since gears 72, 73 turn in opposite directions, the direction of rotation of shaft 65 will be determined by the 5 gear with which the clutch collar is engaged. Before turning the shaft 80, it will be raised slightly to disengage the pin 83 from its 10 recess and when it is released, the pin 83 will fall into another recess to hold the clutch collar in engaging position.

A barrier 84 may be provided across the interior of the gear box 13, this barrier serving as a support for the inner bearing 85 of the shaft 65 and also serving to form an oil 15 pocket between it and the right-hand outer wall of the gear box 13 in Fig. 6, so that the worm 54 can run in oil while keeping the remainder of the gear box relatively free from oil. It will be understood, of course, that 20 while it is desirable to run the worm 54 in oil, it is not desirable to have any more openings than are necessary through which the lubricant can find its way to the exterior of the gear box and for that reason and also because of the easy assemblage which is made 25 possible thereby, I provide the frame 57 so that the bearings for the shaft 56 will be entirely inside of and free from the walls of the gear box. Consequently the only shafts 30 extending through the gear box are the driving shaft 16, the oscillating shaft 17 and the rotating shaft 65, and in each case, only one bearing need be made oil-tight, which may be done in any of the usual manners, such as 35 that illustrated in Fig. 6.

Bracket 66 with its connected wringer and wringer shaft 69 are held in operative position by the latch 47, the bracket 66 having a projection 86 with angular faces, one of 40 which engages operatively with the angled face of a projection 87 on the latch 47 above the pivot 48 thereof. When the bracket 66 is swung to the position shown in Fig. 7, the latch 47 is first rotated counterclockwise and 45 then the projection 87 snaps into place in front of the projection 86. It will be noted that because of the angular relation between the contacting faces of the projections 86 and 87, the bracket 66 is not locked positively but 50 that when considerable pressure is applied to the wringer carried on the bracket 66, the latch will be pushed back against the pressure of the light spring 49 to permit the wringer to be swung counterclockwise in Fig. 55 7, and this will break the clutched connection between the shafts 65 and 69. This arrangement is provided for safety so that in case the operator should become entangled between the wringer rolls, a push will immediately disconnect the wringer driving mechanism and stop the turning of the wringer rolls.

It will be understood that the wringer bracket 66 and the wringer connected thereto 60 can be entirely removed from the apparatus

by lifting the lugs on the bracket from the hinge pins 67, and this is the condition shown in Figs. 1 and 2.

It will be understood that when the washing devices are in use, the wringer is not in use 70 and vice versa and the wringer may be entirely removed from the machine when the washing is being done and similarly the washing apparatus, including the bracket 21, may be removed from the machine when the 75 clothes are being wrung. By the arrangement provided, it will also be obvious that the wringer can be operated either when in the position shown in Fig. 4, directly over the tub or, by turning the sleeve 12 (after 80 the stops 43 are removed), the wringer may be set with its rollers parallel to the front of the tub, as desired. The freely movable base 10 enables the apparatus to be moved into any position which may be found best suitable for the operation of the wringer.

In my copending application, Serial No. 215,329, which has now matured into Patent No. 1,771,629, I have illustrated and claimed broadly a combination of a support and a device hinged thereto, each carrying shafts which are clutched together or disconnected by movement of the device on the hinge. In my copending application, Serial No. 263,222, which has now matured into Patent No. 1,771,630, I have illustrated and claimed a combination of a support and device hinged together, and each carrying shafts which are likewise adapted to be brought into operative or inoperative positions by swinging of the device on the hinge, together with means to yieldingly hold the support and device in operative relation to each other. In this last-named patent, I have also claimed other features including the arrangement whereby 100 said clutch is disconnected upon rotation of one of said shafts in the wrong direction.

It is to be understood that the claims in the present application are not intended to be directed to any of the features enumerated above, or other features covered by the claims in said patents.

It will be understood that the arrangement which I have described is merely illustrative and that the embodiment of my invention may be widely varied. It will also be understood that many of the features of my invention may be used independently of other features.

I claim:

1. In combination, a support resting on the floor and freely movable thereon, a washing apparatus mounted on said support and movable therewith, power devices on said support to drive said apparatus, a tub having a substantially rectangular opening, a bracket connected to said support and extending over the tub, and means to hold said support and its washing apparatus in fixed relation with the tub, including stops bearing 125

against at least two interior corners of the tub and arms connecting said stops with said bracket.

2. In combination, a support resting on the floor and freely movable thereon, a washing apparatus mounted on said support and movable therewith, power devices on said support to drive said apparatus, a tub having a substantially rectangular opening, and a bracket connected to said support and extending over the tub, said apparatus comprising means to hold said support and washing apparatus in fixed relation with the tub, said means including stops bearing against at least two interior corners of the tub and arms connecting said stops with said bracket, said arms being pivotally connected to said bracket to permit the stops to be lifted above the top of the tub.

29 3. In combination, a support resting on the floor and freely movable thereon, a washing apparatus mounted on said support, power devices on said support to drive said apparatus, a tub having a substantially rectangular opening, and a bracket connected to said support and forming part of said apparatus and extending over the tub, said apparatus comprising means to hold said support and washing apparatus in fixed relation with the tub, said means including stops bearing against at least two interior corners of the tub and arms connecting said stops with said bracket, said arms being adjustable in length to bring the stops in proper holding relation to the tub, said arms comprising a pair of superposed members and means to clamp them in extended position.

4. In combination, a support resting on the floor and freely movable thereon, a washing apparatus mounted on said support and movable therewith, power devices on said support to drive said apparatus, a tub having a substantially rectangular opening, said apparatus comprising means to hold said support and washing apparatus in fixed relation with the tub, said means including stops connected to the washing apparatus and bearing against the interior of at least two corners of the tub and a stop connected to the washing apparatus and bearing against the exterior of the tub.

5. In combination, a support resting on the floor and freely movable thereon, a washing apparatus mounted on said support, power devices on said support to drive said apparatus, a tub having a substantially rectangular opening, and a bracket connected to said support and extending over the tub, said apparatus comprising means to hold said support and washing apparatus in fixed relation with the tub, said means including stops bearing against at least two interior corners of the tub and arms connecting said stops with said bracket, said arms being long enough to rest on the top of the tub and the

stops being connected to the arms intermediate the ends thereof.

6. In a washing machine, an oscillating horizontal power shaft, an arm connected to said shaft and oscillating therewith, a pair of downwardly extending rods, each pivotally connected to an end of said arm, a washing bell on the lower end of each rod and a bar pivotally connected to each of said rods and free of other connections, so that it may move longitudinally of itself to permit the bells to move horizontally as they are reciprocated vertically by oscillation of the arm.

7. In a washing machine, an oscillating horizontal power shaft, an arm connected to said shaft and oscillating therewith, a pair of downwardly extending rods, each pivotally connected to an end of said arm, a washing bell on the lower end of each rod and a bar pivotally connected to each of said rods and free of other connections, so that it may move longitudinally of itself to permit the bells to move horizontally as they are reciprocated vertically by oscillation of the arm, and means to limit the extent of such longitudinal motion.

8. In a washing machine, an oscillating horizontal power shaft, an arm connected to said shaft and oscillating therewith, a pair of downwardly extending rods, each pivotally connected to an end of said arm, a washing bell on the lower end of each rod and a bar pivotally connected to each of said rods and free to move longitudinally of itself to permit the bells to move horizontally as they are reciprocated vertically by oscillation of the arm, and means to limit the extent of such longitudinal motion, said means comprising a fixed loop and a pin in said bar and extending through said loop.

9. In a washing machine, an oscillating horizontal power shaft, an arm connected to said shaft and oscillating therewith, a pair of downwardly extending rods, each pivotally connected to an end of said arm, and a washing bell on the lower end of each rod, each bell being pivotally connected to its rod, and cooperating elements on said rod and its associated bell to limit the rotation of the bell on its pivot.

10. In a washing machine, an oscillating horizontal power shaft, an arm connected to said shaft and oscillating therewith, a pair of downwardly extending rods, each pivotally connected to an end of said arm and a washing bell on the lower end of each rod, each bell being connected to its rod by a pivot extending transversely of the plane of said arm, whereby the bell is free to oscillate on its pivot in the plane of said arm, and co-acting elements on each rod and associated bell to limit the extent of oscillation of each bell.

11. In a washing machine, a support, an oscillating power shaft having one end in

said support, a bracket removably connected to said support and having a bearing for said shaft remote from said support, an arm connected to the outer end of said shaft outside said bearing, a washing bell connected to each of the opposite ends of said arm, said shaft being divided into two parts between said bearing and said support and the two parts having a clutched connection when the parts are in operative position, whereby the oscillation of the part of the shaft in said support will oscillate the part in said bearing.

12. In a washing machine, a support, an oscillating power shaft having one end in said support, a bracket hinged to said support to permit the bracket to be swung horizontally, a bearing for said shaft in said bracket, an arm connected to said shaft outside said bearing, a washing bell connected to each of the opposite ends of said arm, said shaft being divided into two parts between said bearing and said support, said parts having a clutched connection therebetween, whereby when the parts are in operative relation oscillatory movement will be transmitted from one part of the shaft to the other, and whereby when said bracket is swung outwardly from the support, said parts will be disconnected.

13. In a washing machine, a support, an oscillating power shaft having one end in said support, a bracket hinged to said support to permit the bracket to be swung horizontally, a bearing for said shaft in said bracket, an arm connected to said shaft outside said bearing, a washing bell connected to each of the opposite ends of said arm, said shaft being divided into two parts between said bearing and said support, said parts having a clutched connection therebetween, whereby when the parts are in operative relation oscillatory movement will be transmitted from one part of the shaft to the other, and whereby when said bracket is swung outwardly from the support, said parts will be disconnected, and a latch to hold said bracket against rotation on its hinge.

ROBERT HOE.
